UNITED STATES PATENT OFFICE.

JOHN STEWART, OF NEW YORK, N. Y.

CLEANING DEVICE FOR DISTRIBUTOR HEADS.

Application filed April 6, 1926. Serial No. 100,123.

My invention relates to distributors or timers of the type generally found in ignition systems for internal combustion engines and which customarily include a head 5 provided with a plurality of contact members for cooperation with a movable distributor arm whereby the electrical ignition circuits are controlled in predetermined sequence. Such contact members in existing forms of distributors, are located in positions more or less difficult to reach, this being the result of the structural form of the distributor and often also of its position in the assembly of which it comprises 10 a part. On the other hand it is essential, in order to provide at all times a maximum operative efficiency, that the active surfaces of these contact members be maintained in a proper condition free from dirt and foreign matter. Because of the relative inaccessibility of the contact members these conditions are difficult of fulfillment and accordingly the contact members are oftentimes permitted to remain uncleansed or otherwise 15 the contour of the active surfaces is altered in the cleaning thereof and in either case the efficiency of the distributor is reduced. The object of the invention is to provide a cleaning device of simple construction 20 whereby the cleaning of the contact members may be easily accomplished and the desired contour of the active surfaces thereof positively maintained. Other more specific objects will appear from the description 25 hereinafter and the features of novelty will be pointed out in the claim.

In the accompanying drawing, which illustrates an example of the invention, Fig. 1 is an elevation, partly in section, of a distributor head showing one form of the cleaning device in operative position; Fig. 2 is a plan view of Fig. 1 with parts broken away; Fig. 3 is a sectional view of the cleaning device, and Fig. 4 is an end face 45 view thereof.

For the purpose of illustrating the device and its operation, I have shown it in a form adapted for use particularly with a distributor of the type included in the well-known Delco system of ignition for automobiles; it will be understood that the device is 50 equally well adapted for use in connection

with the other types of distributors, timers and the like and that the example chosen for illustrative purposes is not intended to define the limits of the invention.

In all of its forms the device comprises a carrier or body 10 provided with a suitable handle or equivalent manipulating member 11 and cleaning means 12. The physical characteristics of the latter are such that said means will accomplish the desired cleaning action either by simply removing the accumulated foreign matter from the surface of the contact members or by at the same time treating the surfaces thereof to restore the original contour thereof. Thus in the illustrated example the cleaning means consists of an abrasive material which not only completely removes dirt and other foreign matter from the surface of the contact members, but coincidentally grinds said surfaces and thereby restores them to their original condition. To accomplish these results in the simplest manner and without the necessity for any particular skill in the use of the device, the latter is constructed in a manner to operatively fit the distributor or timer for which it is designed, and the cleaning element is located so upon the device so as to be properly positioned with respect to the contact member or members without any particular adjustment being required. With this in mind the carrier 10 of the illustrated example, which is designed for use in connection with a distributor of the aforesaid Delco ignition system, is provided with a central recess 13 for the accommodation of the spring controlled contact member 14, which generally comprises part of the distributor head 15 in such system, and the carrier 10 is made of circular form and of such diameter as to fit operatively within the distributor head as will appear more fully hereinafter. As shown in the drawing the cleaning means 12, in such case, may be made in the form of an annular element as illustrated in Fig.

4 and seated within an annular channel 16 formed in the end face of the carrier 10; the cleaning element 12 may be fixed in the annular channel 16 simply by friction or in any other convenient manner. In all forms of the invention the arrangement is

such that the active surface, or its equivalent, of the cleaning element is disposed with respect to the contiguous parts of the carrier so that the cleaning action of said element 12 will not be interfered with and yet will not extend to any objectionable degree beyond the confines of the faces of the contact members 17 which are to be cleaned; thus in the illustrated form the depth of the channel 16 with respect to the cross-sectional dimension of the element 12 is such that the latter projects outwardly beyond said carrier and has its active surface disposed in a plane beyond the end surface of the carrier and which coincides with the location of said contact member 17 in the head 15. The handle 11 is always of relatively large diameter to provide a peripheral surface adapted to be grasped by the human fingers and to facilitate manual rotation of the device and in addition is provided with an end face of relatively large dimensions to fit the palm of the human hand and to provide a comfortable pressure receiving rest therefor; with this arrangement the pressure necessary to bring about a most efficient result is easily applied to the device and manual operation of the latter is facilitated.

In utilizing the device in its illustrated form the distributor head 15 having been removed from the fixed body of the distributor, the carrier 10 is placed within the head 15 with the contact member 14 projecting into the recess 13 and with the active surface *a* of the cleaning element 12 resting upon the contact members 17 which correspond in number for instance to the number of cylinders included in the engine with which the distributor is combined and are connected with the spark plugs thereof by wires 18 in the conventional way. As will be noted in Figs. 1 and 2, the arrangement and dimensions are such that the carrier 10 operatively fits within the head 15; the latter thus serves as a guide for the device and positively positions the same with respect to the contact members 17. The peripheral surface of the carrier 10 or the equivalent portion of an equivalent element is disposed so that in conjunction with the inner surface of the head 15 or an equivalent element, the active surface *a* of the cleaning element 12 will be positioned to act properly upon the contact members 17 in a manner to clean the same and at the same time to restore the surface form thereof. The contact members 17 generally speaking, are embedded in fiber or other non-conductive material 19 with the surfaces of the contact members 17 lying flush with the surface of the material 19, in some systems, as for instance, the one illustrated, the contact members 17 are positioned in the inner end surface of the head 15 while in others they may

be otherwise located. In all forms the device is constructed and dimensioned so that the cleaning means will be properly disposed with respect to the contact members and so as to describe a fixed path of movement with respect thereto when the cleaning device is used for its intended purposes.

Thus in the illustrated example the device is rotated by means of the handle 11 within the head 15 either continuously in a given direction or in a reciprocating manner; in any case the device is positively guided by the head 15 to cause the cleaning element 12 to pass across and in contact with the faces of the contact members 17. The latter are thus easily and quickly cleaned of all dirt and foreign matter, the treatment being continued as long as desired or found necessary. Because of the dimensioning of the device and the relative location of the parts thereof the action of the cleaning element 12 is uniform over all of the contact members 17 as clearly shown in Figs. 1 and 2. As a result of this the surfaces of the contact members 17 are efficiently cleaned and quickly restored to their flat or other predetermined original condition and thereby maintained in a state of maximum efficiency. If the action of the element 12 is abrasive the surfaces of the contact members 17 in addition to being freed from dirt and other foreign matter, are ground to a bright condition of high electrical conductivity.

The device is simple in construction and automatic in action and requires no skill in its use and operation; it provides an implement which reduces a troublesome and difficult cleaning operation to one of the utmost simplicity and thus makes it possible easily to maintain distributors, timers or devices of a kindred nature in a highly efficient condition.

Various changes in the specific form shown and described may be made within the scope of the claim without departing from the spirit of my invention.

I claim:

A cleaning and smoothing device for distributors of the type having fixed contact points arranged on the bottom of a recessed body and having a movable contact point projecting above the bottom of the recess and the fixed contact points at the central point thereof, comprising a cylindrical rigid body dimensioned to snugly and rotatably fit within the recess of the distributor so as to be guided in its rotary movement by the side walls of the recess of said body and having a free end face, a cleaning element formed of abrasive material mounted on said body and projecting axially beyond said face for rubbing engagement with said fixed contact points, an upstanding flange on the free face of the body for positioning the cleaning element on said face, the central part of said

body being recessed for receiving the movable contact point of the distributor when the cleaning element is in engagement with the contact points, and a handle for manipulating said device, said handle being of relatively large proportions to facilitate manual rotation of said body and said clean-

ing element and having an end face of relatively large dimension to fit the palm of the human hand and constitute a pressure receiving rest therefor. 10

In testimony whereof I have hereunto set my hand.

JOHN STEWART.
